CLARENCE A. RICHARD, OF DETROIT, MICHIGAN, ASSIGNOR, BY DIRECT AND MESNE ASSIGNMENTS, OF ONE-THIRD TO OTIS K. RICHARD AND TWO-THIRDS TO CLEMENT C. RICHARD, BOTH OF DETROIT, MICHIGAN.

WORK-HOLDING HEAD FOR LATHES.

Application filed March 3, 1924. Serial No. 696,411.

This invention relates to work holding devices for lathes, grinders and other metal forming devices, the object being to provide a comparatively simple and highly efficient mechanism adapted for the turning, forming or the grinding of metal having an elliptical, oblong, hexagonal, or shape other than round in cross section. In the usual lathe and chuck for holding the work, a round shape only is able to be formed, and this invention seeks to provide a means for moving the work relative to the tool in such manner that other than round shapes may be turned, or ground, if the cutting instrument be a grinding wheel, and of such character that accuracy can be secured and punches and tools and metal parts of odd shape can be readily formed by even an unskilled workman once the machine is adjusted for the particular operation.

The device is adapted for attachment to an ordinary lathe or cylindrical grinder depending on whether a cutting or grinding operation is to be performed. Heretofore, it has been a laborious process to make an accurate punch for instance of an oblong shape in cross section requiring it to be forged and then carefully finished. Also, various other devices, forgings, castings of various forms in cross section, may be machined by this device.

A further object of the invention is to provide a device by means of which oval, oblong and shapes other than round may be formed in which means are provided for adjustment to vary the shape produced through use of the device. These and various other objects and novel features of the invention are hereinafter more fully described and claimed, and a work holding head embodying my invention is shown in the accompanying drawings in

which—

Fig. 1 is an elevation of a device embodying my invention taken from the driving side.

Fig. 2 is an elevation showing the work holding side of the device.

Fig. 3 is a vertical section of the device taken on line 3—3 of Fig. 2.

Fig. 4 is a similar section taken on line 4—4 of Fig. 2.

Fig. 5 is an elevation of the inner face of the driving head.

Fig. 6 is an elevation of the inner face of the driven head.

Figs. 7, 8, 9 and 10 are details of portions of the driving cams on the adjacent sides of the two heads hereinafter more fully described.

The device consists of a stationary body 1 substantially cylindrical in shape and provided with a foot or base 2^a by means of which it may be secured to the bed of a lathe or grinder. Rotatably supported in one side of

this stationary member is a driving head 2 and a driven head 3 is rotatably mounted in the opposite side. The driving head 2 is supported on two sets of ball bearings as shown in Figs. 3 and 4, the inner row of balls 4 riding in a race provided in the stationary member 1 and the member 2 having a coned portion 5 engaging the balls. The second row of balls 6 ride in a race provided in the head 2 which engage a cone faced ring member 7 secured to the stationary head. This ring member 7 is provided at the inner opening with a felt washer 8 providing an oil retainer and means to exclude dust from the bearing. The driven head 3 is likewise similarly mounted and supported by two series of ball bearings, there being a ring 9 provided with a felt washer 10 secured to the stationary member 1 on the forward face. The driving member 2 is provided

with a hub 11 having a central aperture in which the driving shaft 12 is inserted and fastened in place by the taper pin 13. The inner face of the driving head is recessed as indicated at 14 to receive the slide 15, the slide being retained in place by ways 16 shown clearly in Figs. 4 and 5. This slide has a recess 17 of greater length than width, the length thereof extending transversely of the slide 15 as shown in Fig. 4. This recess is open to the back of the slide and the eccentric pin 18 fits in the recess being of the same diameter as the recess is in width, and this eccentric pin is formed on the end of a bar 19 fitting in the forward end of the aperture in the driving head 2 in axial alignment with the shaft 12. This pin 18 is eccentric to the axis of the member 19 as may be understood from Fig. 5 and, by turning the member 19, the slide may be moved or adjusted in position for a purpose hereinafter de-

scribed. The member 19 may be turned by means of the disk or index plate 20. This plate 20 has a mark 21 thereon and may be turned relative to the graduations 22 provided on the portion of the head 2 adjacent the periphery of the plate. The turning of the plate turns the member 19 by means of the pin 23 which extends into an aperture in the member 19 as will be understood from Fig. 3. The pin 23 rides in a slot 24 provided in the driving head as will be understood from Fig. 4, and this slot is cut approximately half through the hub 11 permitting the pin 23 to be turned through approximately 190 degrees. The outer end of the pin engages a notch 25 in the hub of the adjusting plate 20 so that, by turning the plate, the pin is moved through the slot 24 turning the member 19 on its axis. Upon the plate 20 being moved to the desired position, a lock nut 26 is turned up to bind the same in place. The slide 15 has a round boss 27 on the forward face and the recess 17 in the rear face of the slide is at one side of the center or axis of the boss and, by turning the plate 20 relative to the graduations on the member 2, the eccentricity of this boss 27 relative to the axis of rotation of the driving head may be varied.

The driven head consists of the member 3, rotatably mounted as heretofore described, and the work holder designated generally at 28 which may turn with the member 3 and slide on a diametrical line thereof. This work holder consists of the chuck 29 at the forward end thereof held on the member 28 by the member 30 in threaded engagement therewith.

A piece of work is indicated at 31 which is in the nature of a punch and in the body of which is formed a slight recess for the ball 32 in the inclined way 33 formed in the body 29. A pin 34 is also provided in the member 28 projecting into a slot 35 in the rear face of the body 29 to hold the member 29 from rotation. The body 31 of the work here shown is round while the forward projecting end thereof is the part to be shaped. As will be observed from Figs. 3 and 4, this projecting end of the work is formed with flat sides and is narrow in width and is here given as an illustration of only one of the forms that may be made with this apparatus. The two side edges of the projection are rounded edges. To secure this character of result it is necessary that the work be moved relative to the tool, moving in a straight line to form a cut on one side and then again moved in a straight line across a tool and then turned to form the opposite rounded edge. To secure this character of result, the work head 28 is movable in the member 3—that is, from right to left in Fig. 3 through operation of the eccentric boss 27 which engages in a recess of the same width and greater length formed in the slide 36. This slide, as will be understood

clearly from Figs. 4 and 6, has recess 37 for the adjustable eccentric member 27 and the slide is held in position by the members 38 and 39 on opposite sides thereof secured to the inner face of the member 3 by means of screws 40. This slide has the chuck head 28 secured to the inner face thereof by means of the screws 41 so that the chuck head and slide are in integral relation. It is therefore to be seen that, on rotation of the eccentric member 27, a reciprocation of the chuck head and work is provided and, to secure the peculiar form of the work hereinbefore mentioned having a flat side and rounded edges, it is necessary that the work be moved in a straight line across the cutting instrument and then turned through 180 degrees to produce the rounded edge and then moved in a straight line and again turned, the movements being in sequence and automatically secured by this device by alternate periods of rest and rotation of the member 3. To secure rotation and rest periods of the member 3, it is necessary to alternately engage and disengage the driven head with the driving head. To accomplish this, I provide a rock bar 42 which is pivotally supported in the chuck head by means of the screw 43 passing centrally therethrough. The chuck head is slotted to receive this bar and the bar is formed with the two opposite ends 43 and 44 positioned in the recess formed between the inner face of the driving member 2 and the stationary member. On the inner face of the driving member is a practically half circular flat cam ring 45, which is hereinafter termed the driving cam. This cam has one end beveled and notched as indicated at 46 in Figs. 5 and 7 and a beveled and square end 47 as indicated in Figs. 5 and 8. There is also a stationary cam ring 48 mounted in the stationary member 1 which is provided on one side with a notch 49 and an inclined surface 50 leading to the notch and practically diametrically opposite the said notch 49 the ring 48 is provided with a shoulder 51 formed by the outwardly extending inclined surface 52. The lever ends 43 and 44 are indicated in Figs. 7, 8, 9 and 10 and, if it be assumed that the lever end 44 is being driven by the cam 45 and driving head in the direction of the arrow shown in Fig. 7 then, as the said end approaches the incline 50 of the stationary cam 48, the opposite end rides up the incline 52 of the stationary cam ring causing the end 44 to drop into the notch 49 out from in front of the shoulder formed at the end 46 of the driving cam 45, the end 43, due to the cam 52 on the stationary ring, moving behind the end 47 of the rotating driving ring. This locks the end 44 in the notch 49 of the stationary member 48. As this lever 42 is thus locked in position on a stationary ring, the driven head 3 is held from rotation during the interval and it is at this time that the eccentric

27 moves the slide 36 and the chuck head 28 carrying the work in a straight line across the cutting instrument. It is to be noted that the cam end 43, when the lever 42 comes to locked position in the notch 49, has been moved practically to engagement with the inner face of the driving head 2 and thus the said end 43 is in position to be engaged by the inclined end 46 of the cam plate 45 and thus, as this cam end 46 comes around to the lever end 43, the said end rides up on the cam end 46 rocking the lever 42 and raising the end 44 out of the notch 49 and thus starts to drive the driven head and will continue to drive through a succeeding half turn around again to the position of the parts shown in Fig. 7 whereupon the driven head is again locked from rotation and the chuck head is caused to slide. It is therefore to be seen that the driven head by the cam ring arrangement described is turned for practically a half revolution and then is held stationary for practically a half revolution during which time the work is moved across the tool and then again the driven head and the work is rotated causing the work to be turned relative to the cutting instrument to form the rounded edge heretofore mentioned.

Depending upon the eccentricity of the member 27, the length of the straight cut on the work is determined. Likewise, the distance of the edge of the work from the center of rotation of the head 3 will determine the arc of the circle through which the said edge is turned relative to the cutting instrument and thus shapes of various sizes similar to the shape of the recess 37 of Fig. 6 may be made by the arrangement of the cam rings and the parts hereinbefore described. These shapes may be varied from a true oval form or forms other than a round shape or even a round shape if the axis of the member 27 is set exactly on the axis of the member 3 and the variation in form is dependent upon the cam ring arrangement. Evidently, if a true oval form is desired, there could be no period in which rotation of the member 3 ceased; therefore, the chuck head must be moved in its slide during rotation of the member 3. Thus, various shapes can be made by varying this cam arrangement and the time of the locking of the head 3 from rotation relative to the time at which the cam member slides.

It is to be noted that the eccentric 18 is merely for the purpose of adjusting the eccentricity of the member 27 relative to the axis of rotation of the driving and driven head. The chuck head 28 extends through an aperture 60 in the member 3 of greater diameter than the body of the head 28 permitting the member 28 to be moved with the slide. Preferably, a plate 61 is provided on the member 28 covering the aperture 60 as will be understood from Fig. 4 to prevent dust

and dirt from getting into the interior of the device. Also, a felt ring 62 is provided engaging the inner face of the plate 61. I have here shown a peculiar type of chuck for the work, but it is to be understood that this 70 chuck head may be of any accepted form for holding the work without departing from the spirit of this invention.

The members 2 and 20 in fact provide two dials and in setting the device the shaft 12 is 75 released from the driving element to enable the member 2 to be turned by hand usually by rotation of the hub 11. The nut lock 26 is first loosened to permit turning of the member 20 relative to the member 2 then the 80 member 2 may be set or turned manually to any desired position, and the member 20 then turned in the same direction to secure the fine graduation desired. It is to be noted that, in this setting of the members 2 and 20, 85 the member 2 is rotated through the slide producing pressure thereon. There is thus a peculiar relationship of the two dials, either of which may be manually turned, the main dial 2 being set to any desired position to 90 turn an adjustable member and then the secondary dial 20 turned to secure the exact final adjustment desired so as to position the head 27 and adjustable member 31 in exactly the desired relationship either directly on the 95 center of rotation of the member 2 or eccentric thereto if desired.

It is evident from the foregoing description, that the cam may be arranged to provide for a continuous driving of the member 100 3 or arranged to produce the alternate periods of rest and rotation of the member 3, and further that these periods of rest and rotation may be for less than a half revolution of the member 3. The form of cam rings, 105 as shown by the drawing, provide for a period of rest for half a revolution of the driving member and a period of rotation for half the revolution of the driving member. This, as before stated, is merely illustrative of the 110 arrangement of the rings for the formation of the described shape of the work in cross section. By arranging the stationary cam ring for six successive periods of rest and rotation of the driven member, a form hexagonal in cross section may be produced, and it is to be understood that these and other various changes of the mechanism for the 115 driving of the member 3 are within the spirit of this invention as set forth in the appended 120 claims.

What I claim and desire to secure by Letters Patent of the United States is—

1. In a work holding head, a stationary body, a driving member and a driven member 125 rotatably supported therein in axial alignment, a work holder carried by the driven member and rotatable therewith, the work holder being provided with an elongated way, an eccentric on the driving member 130

adjustable as to its distance from the axis of rotation thereof and engaging in the way whereby, during rotation of the driving member, the work holder is intermittently caused to move on a diametrical line of the driven member, a rock lever pivotally mounted relative to the driven member having the opposite ends extending into an annular recess provided between the inner face of the driving member and the stationary body, a cam ring on the driving member, a complementary ring on the stationary member, the rings being so arranged that the lever is intermittently rocked, first locking the driving and driven members together and then holding the driven member stationary, and an index plate for determining the eccentricity of the said eccentric.

2. In a work holding head, a stationary body, a driving member rotatably supported therein, a driven member also rotatably mounted therein on the same axis, automatic means for successively connecting and disconnecting the driving and driven members, a work holder carried by and rotatable with the driven member, said work holder having an elongated way or recess therein, an eccentric engaging in the said way and carried by the driving member, the eccentric being of a diameter equal to the width of the way and less than the length of the way whereby, during rotation of the eccentric, the work holder is caused to move intermittently on a diametrical line of the driven member, the said automatic means operating to disconnect the members during each movement of the work holder, and means for varying the eccentricity of said eccentric member relative to the axis of the driving member.

3. In a work holding head, a stationary body, a continuously rotatable driving member supported therein, a driven member rotatably mounted therein, a rock lever adapted when rocked in one direction to lock the driving and driven members together and when rocked in the opposite direction to hold the driven member stationary, means for rocking the said lever intermittently, a work holder carried by the driven member and rotatable therewith, said work holder being mounted to slide in the driven member on a diametrical line, and means on the driving member for sliding the work holder first in one direction and then in another during alternate stationary periods of the driven member.

4. In a work holding head, a continuously rotatable driving member, a rotatably mounted driven member, a rock lever adapted to connect and disconnect the driving and driven members, means actuated by the driving member for first rocking the member to lock the driving and driven members and then to oppositely rock the member to disconnect the driving and driven members, a work holder carried by the driven member and movable

on a diametrical line thereof, and means for moving the work holder during the time the driving and driven members are disconnected.

5. In a work holding head, a continuously rotatable driving member, a rotatably mounted driven member, means for automatically connecting and disconnecting the driving and driven members in such manner that the driven member is held stationary during a half revolution of the driving member and is rotated with the driving member for the remaining half of the rotation thereof, a work holder rotatable with the driven member, and means for moving the work holder across the axis of rotation of the driving member during the stationary period of the driven member.

6. In a work holding head, a continuously rotatable driving member, a rotatable driven member, means for automatically connecting and disconnecting the driving and driven members whereby the said driven member is alternately rotated and held stationary, a work holder carried by the driven member, means causing the work holder to move radially of the driven member during its stationary period, and means for varying the extent of radial movement of the work holder.

7. In a work holding head, a stationary body, a driving member rotatably supported therein, a driven member rotatably supported in said body in axial alignment with the driving member, a work holder carried by the driven member and rotatable therewith, means for intermittently holding the driven member from rotation, and means for causing the work holder to move across the axis of rotation of the driven member during the period in which the driven member is held stationary.

8. In a work holding head, a rotatable driving member, a rotatable driven member, a work holder carried by the driven member and rotatable therewith, means whereby the work holder is moved in a straight line each side of the axis thereof during rotation of the driving member, and automatic means for holding the rotatable member from rotation during said movement of the work holder.

9. An index head for an adjustable element comprising a head, an adjustable element, means connecting the head and the element, a main and a secondary dial rotatable on the same axis and both said dials by rotation being adapted to turn the member to be adjusted, the main dial directly turning the adjustable member whereby a coarse degree of adjustment is attained, and the secondary dial operating to turn the main dial and the adjustable member to a finer degree of adjustment.

In testimony whereof, I sign this specification.

CLARENCE A. RICHARD.
